(57) **CLAIM**

The ornamental design for a panel mount housing for an electrical connector, as shown and described.

DESCRIPTION

FIG. 1 is a perspective view of a panel mount housing for an electrical connector, showing my new design;

FIG. 2 is a left-side elevation view thereof;

FIG. 3 is a right-side elevation view thereof;

FIG. 4 is a front elevation view thereof;

FIG. 5 is a rear elevation view thereof;

FIG. 6 is a top plan view thereof; and,

FIG. 7 is a bottom plan view thereof.

The (equally-sized) dash-dash broken lines shown in the drawings depict portions of the panel mount housing electrical connector that form no part of the claimed design. The (unequally-sized) dot-dash-dot broken lines in the drawings are included for the purpose of defining the boundary of the claim, it being understood that the dot-dash-dot broken lines themselves form no part of the claimed design.
